TOY MACHINE GUN

Samuel I. Berger, Newark, N. J.

Application May 19, 1947, Serial No. 748,950

2 Claims. (Cl. 46—10)

1

This invention relates to mechanical toys and more particularly to a toy machine gun of the spring motor driven type.

As conducive to a clear understanding of the invention, it is to be noted that in the assembly of a toy machine gun of the conventional type, the parts of the spring motor actuating the same are generally mounted on one side of the frame of the gun and the other side is thereupon affixed to the first side to complete the assembly. If, after the gun is completely assembled, the motor should prove to be defective, the gun must be completely disassembled, repaired and reassembled, which procedure is so time consuming and costly that it is more economical to discard the entire toy.

It is accordingly among the objects of my invention to provide a toy machine gun of light, rugged and inexpensive construction, which has substantially all the advantages of that of my previous application Serial No. 668,290, filed May 8, 1946, now Patent No. 2,530,803, including the use substantially only of sheet metal and rod stock, to simulate the appearance of a genuine machine gun, which is realistic in operation by simulating the clatter of a machine gun and the flash at the muzzle, which in use is not likely to cause injury to the child and which has the advantage over said prior invention of greater simplicity in construction and ease in assembly and replacement of the motor if on inspection and test, the device be found to be defective.

In the accompanying drawings in which is shown one of various possible embodiments of the several features of the invention,

Fig. 1 is a top elevation of the toy,

Fig. 2 is a side elevation thereof with parts broken away,

Fig. 3 is a fragmentary sectional view on a larger scale taken on line 3—3 of Fig. 1,

Fig. 4 is an end view from the muzzle of the gun,

Fig. 5 is a transverse sectional view taken on line 5—5 of Fig. 2,

Fig. 6 is a transverse sectional view taken on line 6—6 of Fig. 3,

Fig. 7 is a sectional detail view taken on line 7—7 of Fig. 2,

Fig. 8 is a sectional detail view taken on line 8—8 of Fig. 2, and

Fig. 9 is a perspective view of the spring motor drive unit.

Referring now to the drawings, the gun comprises a body 10 which is a casing composed of two complementary sheet metal stampings 11

2

and 12, each forming an outline which includes the stock 13. The two complementary pieces are assembled together by crimping the edge 14 of one about the angle formation 15 on the other to form a seam 16. One of the complementary pieces 11 has a substantially rectangular aperture 17 therein into which a spring motor drive unit 18 may be inserted. The edge of aperture 17 has a countersunk flange 17' unitary therewith on which a cover plate 19 having a slot 19' therethrough, may be seated so as to be flush with the surface of complementary piece 11. The cover plate 19 is affixed over said aperture by means of lugs 20 unitary with the edge of the flange 17' and extending through corresponding openings 21 in said cover plate 19.

The barrel 22 is made of a single piece of sheet metal corrugated at 23 to simulate cooling vanes, uncorrugated at its front or muzzle 24 which has a pair of sights 24' preferably embossed thereon, and provided with side pieces 25 unitary therewith. The rear edge of the barrel unit is crimped to the forward edge of the body unit as at 26 by a seam similar to that above described and shown in Fig. 8.

The spring motor drive unit 18 may be of more or less conventional construction and comprises a substantially rectangular box-like frame 27 of sheet metal open at the top and bottom thereof and slightly smaller in face dimensions than aperture 17 in the body 10 of the gun so that it may readily be inserted thereafter the constituent parts of the motor are assembled on the frame. The top edges of frame 27 have a plurality of upstanding lugs 28 unitary therewith by means of which the frame 27 may be securely affixed to the top 29 of the body, the lugs being insertable in corresponding openings 30 in said top 29. The spring motor includes a coil spring 31 within its cylindrical shell 32 and wound around a shaft 33 journaled in openings in the side walls 34 and 35 of the frame and extending laterally outward from wall 34. The coil spring 31 is wound by means of a key conformation 36 on the end of shaft 33 and a conventional winding pawl and ratchet (not shown). Shell 32 has a gear 37 affixed thereto which meshes with a pinion 38 on countershaft 39 which countershaft also carries a gear 40 which in turn meshes with pinion 41 on a second countershaft 42 which carries a crown gear 43, the latter driving a pyrophoric flash simulation unit which will be described hereinafter.

Countershafts 39 and 42 are journaled in openings in side walls 34 and 35 of the frame as is countershaft 44 which carries a gear 45 preferably

meshing directly with gear 37 and a clapper actuating ratchet wheel 46 which simulates the sound of a machine gun and the operation of which will be described below.

Flash simulation is effected by an abrasive wheel 47 driven from the spring motor and a pyrophoric tip or flint 48 riding on the periphery thereof. The abrasive wheel is keyed upon an axle 49 along with a pinion 50, the axle bearing in sheet metal standards 51, the latter being part of a substantially U-shaped bracket 52 affixed to closure plate 53 bridging across the lower edges of the side walls 25 of the barrel by lugs or tines 54. The flint 48 is riveted to a sheet metal strip 55 with a bent-out heel 56 extending through a corresponding slot 57 in the upper part of the muzzle 24 and with end tongues 58 overlapping the muzzle and loosely supporting the strip 55.

The transmission from crown gear 43 of the spring motor to the abrasive wheel 47 is by way of a drive rod 59 which passes through an opening 59' in wall 69 of the frame 18 and bears at one end in an arm 60 turned inwardly from side wall 34 of the frame 27 and unitary therewith and at its opposite end in the upper part of a cross-plate 62 bridging between and preferably integral with the standards 51. Affixed to the rear end of the drive rod 59 in front of arm 60 is a pinion 63 which meshes with the crown gear 43, and at the forward extremity of said rod 59 beyond the bearing or cross plate 62 is keyed the hub 64 of a crown pinion 65 meshing with the pinion 50.

The clatter producing member is a short leaf of spring steel 66 riveted as at 67 to the under face of the upper wall of the barrel at the root end thereof, with a portion 68 thereof normally in juxtaposition to the under face of the top wall 29 of the body 10, the forward part of said leaf extending through an opening 66' on the front wall 69 of the frame and in the path of the teeth of ratchet wheel 46.

The motor is normally restrained by a brake, comprising preferably a sheet metal pawl 70 pivoted by a rivet 71 to the side wall 34 of the frame 27 and having a pawl tongue 72 which meshes with the pinion 63, as best shown in Fig. 5. The pawl is retained in such meshing position by a flexed spring wire 73 releasably pivoted as at 74 at its forward end to the lower end of the pawl 70, and extending the length of the body and reacting at its opposite end against the back wall 10' of the body. Release of the motor and operation of the toy is effected by a trigger which comprises a bar 77 pivotally mounted as at 78 to the side of complementary piece 12 and having its trigger end 79 exposed for operation through a trigger slot 80 in the body. The wire 73 extends through an aperture 73' in said trigger bar slightly above the trigger and has a right angled bend 74' therein against which the trigger bar presses.

Installation and operation

The body of the gun is assembled together with the clapper strip 66, the flash simulation device comprising the abrasive wheel 47, pinion 50, crown pinion 65, drive rod 59, pinion 63 and trigger 75 with flexible wire 73. The constituent parts of the spring motor drive unit 18 are assembled on frame 27 and the end of drive rod 59 is inserted through the opening 59' in wall 69 of the frame into the bearing opening in arm 60 so that pinion 63 meshes with crown gear 43. The forward end of wire 73 is inserted into the lower end of the pawl 70 and the drive unit 18

is then positioned in aperture 17 in body 10 so that clapper strip 66 enters opening 66' in wall 69 with its free end in juxtaposition to ratchet wheel 46. The tines 28 on the top of frame 27 are inserted through the openings 30 in the body 10 and bent over securely to hold the motor unit in place. Cover plate 19 is placed over aperture 17 and seated on flange 17' so that key conformation 36 passes through slot 19' and the tines or lugs 20 pass through the openings 21 in the cover plate. These tines are then bent over to complete the assembly.

The motor being wound, the gun is operated by pulling the trigger 75 which, through the wire 73, releases the pawl 70 from the pinion 63. The spring motor thereupon drives the crown gear 43 at fairly high speed and through the pinion 63, drives rod 59 and crown pinion 65, spins the abrasive wheel 47 so that flint 48 riding thereon generates sparks which are propelled outward through the muzzle 24 giving the simulation of a flash.

The clapper ratchet wheel 46 driven from the motor alternately pushes the clapper strip 66 downward drawing it away from the body wall 29 and upon quick release thereof, causes portion 18 thereof to strike said wall with the clatter desired.

Upon release of the trigger 75, the spring wire 73 pushes bar 77 forward about its pivot 78 and the bar 77 in turn moves the front portion of wire 73 forward to pivot pawl 70 back into engagement with pinion 63 and brakes the motor pending subsequent operation.

As the motor is a complete unit in itself, it may conveniently be tested before insertion into the body of the gun, and if after insertion, it should fail to work it can quickly and easily be replaced by a new unit without discarding the entire gun. This feature increases the speed of assembly of such toy guns and greatly reduces the cost thereof.

As the only parts likely to wear out after continued use of the gun are the abrasive wheel and the flint, these parts are made readily available for repair or replacement by simply spreading the tines holding the closure plate 53 and removing the latter along with the U-shaped bracket 52 affixed thereto and mounting the abrasive wheel. With the closure plate 53 removed, the flint 48 is exposed and can be easily removed.

As many changes could be made in the above construction and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. A toy machine gun comprising a body having an aperture therein on one side thereof, a barrel having a muzzle affixed to said body and extending longitudinally thereof, a spring steel clapper riveted at one end adjacent to the rear end of said barrel and extending into said body, a drive unit having a spring motor removably mounted in said aperture, a cover plate removably affixed to said body over said aperture, thereby closing the latter, a ratchet wheel mounted on said drive unit and driven by said spring motor, said ratchet wheel having teeth riding over the free end of said clapper, said clapper having a portion striking the body after each deflection and release thereof.

by said ratchet wheel, a spark producing flint in the muzzle, an abrasive wheel coacting therewith, and a transmission comprising a drive rod longitudinally of said barrel extending from said abrasive wheel into said body, a pinion affixed to the end of said drive rod in said body, a crown gear journaled in said removable drive unit and meshing with said pinion to drive the latter and rotate said abrasive wheel, a brake for said motor comprising a pawl pivoted to said body and resiliently urged into engagement with said pinion, and a trigger pivotally mounted on said body and connected to said pawl to disengage the latter from said pinion.

2. The combination set forth in claim 1 in which said barrel has a pair of side pieces unitary therewith and extending downward therefrom, a closure plate bridging across the lower edges of said side pieces and removably affixed thereto, a

pair of standards affixed to said closure plate, an axle bearing in said standards, said abrasive wheel keyed on said axle, a strip affixed at one end to said barrel and a flint at the free end of said strip and resting on said abrasive wheel.

SAMUEL I. BERGER.
